ELECTRIC CAN OPENER HOUSING

Bernard Klassen, Fremont, Melvin H. Best and Robert S. Inlow, Pasadena, James M. Powell, Anaheim, and William J. Ward, Monterey Park, Calif., assignors to Klassen Enterprises, Inc., Hayward, Calif., a corporation of California

Application September 11, 1957, Serial No. 47,698

Term of patent 14 years

(Cl. D22—2)

Figure 1 is a front perspective view of an electric can opener housing showing our new design;

Figure 2 is a front elevational view thereof;

Figure 3 is a bottom plan view; and

Figure 4 is a rear elevational view.

The dominant portions of our new design are illustrated by the solid line representations in the drawing.

We claim:

The ornamental design for an electric can opener housing, substantially as shown and described.
